UNITED STATES PATENT OFFICE.

HARRY F. FISHER, OF COLUMBUS, OHIO, ASSIGNOR TO THE FISHER-CHASE COMPANY,
OF COLUMBUS, OHIO, A CORPORATION OF OHIO.

FUSE-BOX.

1,318,655.

Specification of Letters Patent. Patented Oct. 14, 1919.

Application filed July 26, 1917. Serial No. 182,867.

To all whom it may concern:

Be it known that I, HARRY F. FISHER, a citizen of the United States, residing at Columbus, in the county of Franklin and State of Ohio, have invented a certain new and useful Improvement in Fuse-Boxes, of which the following is a specification.

This invention relates more particularly to fuse boxes for high tension electric conductors and has for its object to make improvements in the details of construction whereby their operation is facilitated, made more reliable and less dangerous to those who manipulate them.

The invention is embodied in the example herein shown and described, the features of novelty being finally claimed.

In the accompanying drawing—

Figure 1 is a front view of the fuse box with the door opened and disclosing the interior details.

Fig. 2 is a vertical section on the line II—II Fig. 1 looking to the right.

Fig. 3 is a plan view of the lower side of the pull rod.

Fig. 4 is a detail sectional view on a larger scale of the upper end of the fuse container.

In the views 5 designates the box and 6 a door therefor hinged, as at 7, to close the front of the box. 8 designates a stone or porcelain insulating base suitably mounted and secured in the left hand side of the box. The base has upon it suitable binding posts 10, and 11 for connecting the electric line conductors which are passed into and out of the box through suitable porcelain bushings 5^a. Mounted on the base in electrical connection with the binding posts are 40 clips or female members 13 of a knife switch. 14 designates the fuse container, the same being a tube of suitable insulating material but having on its upper and lower ends metallic thimbles 15, 15^a, the upper one, 15, being threaded to receive a metallic plug 16. The plug 16 has a stud 17 to receive a screw 18 for the purpose of binding the fuse wire 19 to it. The other end of the fuse wire which extends through the tube is 50 secured in a binding post 20 on the outer side of the thimble 15^a. The fuse container has knife switch members 21 to make contact with the female switch members 13.

22 designates the pull rod. This pull rod 55 is of insulating material and is mounted to

slide longitudinally in a metallic thimble or bushing 23 mounted on the right hand wall of the box. The outer end of the pull rod is provided with a suitable handle 24 by means of which the rod may be conveniently slid or rocked in its bearing and the inner end of said rod is provided with a bifurcate member 25, the forks of which are provided with pins to enter corresponding sockets in a cross piece 26 on the fuse 60 container. By these means the fuse container is firmly but removably supported in a position at right angles to the direction of movement of the pull rod. The lower side of the pull rod is made with a longitudinal 70 slot 27 which is enlarged laterally at its left hand end as seen at 27^a, said slot being engaged with a pin 28 in the thimble or bushing 23 so that when said pin engages the slot 27 the rod may be pulled or pushed in 75 a right line; and when said pin is opposite the enlarged portion 27^a the pull rod may be rocked on its axis to turn the fuse container support into position for convenient reception and removal of the fuse container. 80 By positioning the pairs of contacts 13, 13 and 15, 15^a so that they are maintained in parallel relation to each other the electrical connection and disconnection of the circuit through the fuse is made instantaneous and 85 practically complete upon the appropriate movement of the pull rod.

In the bottom of the box just below the lower end of the fuse container, when that member is in circuit closing position, is an 90 orifice in which is fitted a thimble 29 provided with a screen 30 to catch the debris of a burnt fuse.

Because the upper end of the fuse container is enlarged and plugged or closed at one end 95 like the barrel of a gun the gases generated by the burning of the fuse cause an expulsion of the debris through the thimble 29.

The practice with this invention is to pull out the fuse before opening the door of the 100 box, and to close the door before shoving the fuse into circuit closing position. In this way possible "flashing" of flame in the face of the operator and the dangers an annoyance incident thereto are avoided. But the present construction makes such "flashing" or 105 sparking or heating far less probable because of the simultaneous, wide or equal separation of the contacts.

Changes can be made in the forms of the 110

parts without departing from the gist of the invention as claimed.

What I claim is:

1. In combination with a fuse box for high tension electric conductors having a pair of stationary clips, a pull rod longitudinally movable in a wall of said box and having at its inner end a seat for a fuse container, a fuse container having a pair of contacts to coöperate with the aforesaid stationary clips and also having means for seating the fuse container on its seat on the pull rod so as to be freely removable therefrom, means whereby said pull rod may be rocked on its axis when the contacts of the fuse container are withdrawn from the stationary clips and means whereby the pull rod is precluded from longitudinal movement when so turned on its axis.
2. In combination with a fuse box for high tension electric conductors having a pair of stationary clips, a pull rod longitudinally movable in a wall of said box and having at its inner end a seat for a fuse container, a fuse container having a pair of contacts to coöperate with the aforesaid stationary clips and also having intermediate said contacts

means for seating the fuse container on its seat on the pull rod so as to be freely removable therefrom, means whereby said pull rod may be rocked on its axis when the contacts of the fuse container are withdrawn from the stationary clips and means whereby the pull rod is precluded from longitudinal movement when so turned on its axis. 30 35

3. In combination with a fuse box for high tension electric conductors having a pair of stationary clips, a pull rod longitudinally movable in a wall of said box and having at its inner end a seat for a fuse container, a fuse container having a pair of contacts to coöperate with the aforesaid stationary clips and also having means for seating the fuse container on its seat on the pull rod so as to be freely removable therefrom, means whereby said pull rod may be rocked on its axis when the contacts of the fuse container are withdrawn from the stationary clips, means whereby the pull rod is precluded from longitudinal movement when so turned on its axis and means for guiding said pull rod to cause the engagement of said contacts with said clips. 40 45 50

HARRY F. FISHER.
